PLASTIC COATED SHEET MATERIAL

James F. Fulton, Birmingham, Mich., assignor to United States Rubber Company, New York, N. Y., a corporation of New Jersey

Application June 22, 1955, Serial No. 36,626

Term of patent 14 years

(Cl. D92—1)

The figure of the drawing is a plan view of a plastic coated sheet material showing my new design.

A complete design unit is included within the dot and dash lines, and this unit is reproduced in regular succession throughout the width and length of the sheet material.

This application is a continuation-in-part of my prior copending application Serial No. D. 29,059, filed February 17, 1954, which is now abandoned.

I claim:

The ornamental design for a plastic coated sheet material, as shown and described.
